WATER CLOSET WITH AUXILIARY CHAM-
BER FOR A CLEANING BRUSHPierre Jean-Marie Théodore Allard,
Chantilly, FranceApplication April 9, 1946, Serial No. 660,789
In France February 1, 1946

2 Claims. (Cl. 4—97)

1

The broom, mop, or similar device used for cleaning the bowl of a water closet is generally placed in a receptacle independent of the closet and located nearby.

According to one feature of the invention, the bowl of the water closet is provided with a chamber adapted to receive said broom. Said chamber is preferably in communication with the inlet pipe for the flush water and with the bowl by one or more openings, whereby the broom is automatically cleansed by the flush water whenever the flush apparatus is operated. The broom is preferably so constructed that it will act as a cover for the broom compartment. Said compartment may be made either integral with the bowl or constitute a separate unit which may be inserted between the flush piping and the bowl.

In the accompanying drawing given by way of example:

Fig. 1 is a vertical section of a closet provided with a broom holding compartment integral therewith.

Fig. 2 is a vertical section through said compartment.

Fig. 3 is a similar section showing a slightly modified construction.

Fig. 4 is a similar section of another construction embodying an auxiliary chamber adapted to contain a deodorizing substance.

Fig. 5 is a similar section of an embodiment in which the broom compartment is independent of the closet and removably mounted.

In the embodiment shown in Figs. 1 and 2, the bowl 1 of the closet is provided externally on its rear face with a compartment 2 integral therewith. Said compartment is in communication by an opening 3 with the inlet conduit 4 for the flush water and by an overflow opening 5 with the inner capacity of the bowl.

The compartment 2 is adapted to receive the broom or mop 6 to be used for cleaning the bowl 1. Said broom is provided at the base of its handle 7 with a disc or plate 8 which will rest upon the upper edge of the compartment 2 and act as a lid.

In the construction shown in Fig. 3, the opening 5a affording a communication between the broom compartment and the bowl opens at the bottom of the compartment so that all the cleansing water will be discharged from said compartment.

In the construction shown in Fig. 4, an auxiliary chamber 10 containing a disinfecting liquid 9 is provided laterally on the broom compart-

2

ment and communicates by a siphon 11 with the opening 3 provided between the inlet conduit 4 for the flush water and the broom compartment 2. When the flush water flows down into the bowl and through the compartment 2, the disinfecting liquid is thus sucked in through the siphon 11 and the broom compartment together with the broom are disinfected at the same time as the bowl.

As shown in Fig. 5, the broom compartment may constitute an independent unit which may be fitted to existing installations. The broom compartment 2 is then provided with a pipe section or coupling 14 integral therewith and is in communication with the same through inlet holes 3 and outlet holes 5. The inlet pipe 13 which extends from the flush tank (not shown) is cut off and connected to the upper end of pipe 14 whose lower end is inserted into the usual opening 15 of the bowl. When the flush apparatus is operated, a certain amount of the flush water under pressure enters the compartment 2 through the holes 3. Said water will thus cleanse the compartment and the broom and run off through the openings 5. An auxiliary chamber for a disinfecting liquid may also be provided in said construction on the side of compartment 2, as described above.

In the various embodiments described above, the lid 8 formed on the broom handle can be provided with a fastening device of the screw type or any other type, in order to prevent the lid from being lifted by the pressure of the flush water in the broom compartment. It will be observed that said pressure is controlled by the comparative sections of the inlet and outlet openings 3 and 5. Said pressure can also be adjusted by providing a restricted portion or nozzle 16 (Fig. 1) in the inlet conduit 4 so as to create a temporary overpressure in compartment 2.

The broom can be made of two removable parts so that the bristle part can be easily changed when worn out.

Having now described my invention what I claim as new and desire to secure by Letters Patent is:

1. In combination with a bowl for water closet comprising an inlet pipe adapted to discharge flush water into said bowl and an auxiliary chamber communicating with said bowl and said inlet pipe and adapted to be crossed by a part of the flush water, a broom comprising a cleaning brush for said bowl and means for supporting said broom on the upper edge of said chamber in such a position that the brush is located in the

chamber and in the path of the flushing water flowing through said chamber.

2. An auxiliary chamber adapted to be inserted between a bowl for water closet and the inlet pipe for the flush water and to be crossed by said flush water which comprises a broom embodying a cleaning brush and means for supporting said broom on the upper edge of said chamber in such a position that the brush is located in the path of the flushing water flowing through said chamber. 10
